UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

REGULATOR FOR DYNAMO-ELECTRIC MACHINES.

SPECIFICATION forming part of Letters Patent No. 278,640, dated May 29, 1883.

Application filed February 23, 1883. (No model.)

To all whom it may concern:

Be it known that I, EDWARD WESTON, a subject of the Queen of Great Britain, and a resident of Newark, in the county of Essex and State of New Jersey, have invented certain new and useful Improvements in Dynamo-Electric Machines, of which the following is a specification; reference being had to the drawings accompanying and forming a part of the same.

10 My invention relates to devices that regulate dynamo-electric machines with respect to the amount of current generated, so that the same volume of current may be produced by the machine at all times, although the resistance of the external circuit varies.

In carrying out my invention I employ as the generator a dynamo-electric machine in which field-of-force magnets are excited by a circuit derived from the main or armature circuit, and in this field-circuit I insert a variable resistance which is operated by an electromagnet included in the armature or main circuit. In this combination—viz., a machine of the kind specified and regulating devices arranged as described—my invention is mainly comprised.

The mechanism devised by me for carrying out more practically and effectively the invention also possesses certain features of novelty which I regard as forming part of my present invention, and which are pointed out in the claims hereto annexed.

In describing the principle of the construction and mode of operation of my invention, I will refer to the accompanying drawings, in which Figure 1 is a side elevation of the mechanism for imparting movement or operating the adjustable resistance or rheostat. Fig. 2 is a plan and part sectional view of the same. Fig. 3 is a view in perspective of the machine, the rheostat, and regulator combined for operation.

The main parts of the regulating mechanism are as follows:

45 A is a shaft, which is driven at a moderate speed from any convenient source of power, a band-wheel, *a*, being fixed to it for this purpose.

B is a swinging lever or frame, oscillated by

the rotation of shaft A through the instrumentality of a crank-rod, C, pivoted to an adjustable slide, *c*, carried by the slotted disk *b* on the shaft A.

D is an arm or frame, to which is connected one end of an adjustable spiral spring, S, the other end being attached to a lever, E, pivoted to the frame B. This lever E carries two arms, *e f*, provided with hinged pawls *e' f'*, the arms being bent so that they do not lie in the same vertical plane. Between arms *e* and *f* are placed two ratchet-wheels, *g d*, with teeth turned in opposite directions, and so arranged with reference to the pawls *e' f'* that the shaft F, to which they are fixed, is turned forward or backward by the engagement with wheel *g* of pawl *e'*, or with wheel *d* of pawl *f'*, the raising or lowering of lever E determining which pawl shall operate. Below the wheels *g d* is an electro-magnet, G, the armature H of which is carried by a frame swinging on a pivot at *h*, and connected by a link, *b*, with the lever E. An arm, K, attached to armature H, is provided with an adjusting-screw for limiting its downward movement, and is connected to the cylinder of a dash-pot, L, the piston *m* of which is hinged to the frame D. An adjustable stop, *n*, limits the upward movement of the armature H. The shaft F is operatively connected with any ordinary rheostat or adjustable resistance, V, so that a movement of rotation of said shaft in one direction introduces more resistance in the circuit including the rheostat, while an opposite movement cuts out resistance.

It is evident that under proper and now well-understood conditions the devices described may be used in various ways in conjunction with a dynamo-electric machine as a regulator. The purpose for which they are more particularly designed is to maintain a uniform flow of current from a machine in the circuit of which are included electrical devices—such as arc-lamps—in series. For this purpose I include the magnet G in the main circuit of the machine, by which the arc-lamps or similar devices are run in series, and insert the rheostat in a circuit which is derived from the main and which energizes the field-magnets

of the generator. Under this arrangement the quantity of current produced by the machine will be maintained uniform, for should one or more lamps be cut out of circuit, or should the speed of the engine run up, the magnet G becomes more highly excited and draws down the armature H and the lever E. This causes pawl e' to engage with ratchet-wheel d, and turns the shaft F so as to bring more resistance into the field-circuit. This continues until the strength of the magnet G and spring S balance. On the contrary, should more lamps be added to the circuit, or the speed of the engine run down, the pawl f' is brought into operation by the force of spring S preponderating over the attraction of magnet G, and the wheel d is turned so that resistance is cut out of the field-circuit. By this means a sensitive regulation of the current generated is maintained, the devices operating to maintain a constant current strength for all variations in the resistance of the line, and to compensate for changes in speed or other causes which tend to vary the current produced.

In order that the shaft F may not be turned by the ratchet-wheels g d too far in either direction, the ratchet-wheels are left blank at a point, as t, on each wheel.

By means of the adjusting-screw s the tension of spring S is varied, so that the regulator may be set for use with a circuit of any given normal resistance. Slight or momentary fluctuations of the circuit do not impart a vibration to the lever E on account of the retarding influence of the dash-pot L.

I am aware that the magnetic intensity of the field-magnets of dynamo-machines has been varied heretofore through the instrumentality of an electro-magnet in the main circuit. I am also aware that the resistance of the field-circuits of dynamo-machines has been varied by means of electro-magnetic regulating devices operating upon the machine in such manner as to cause it to produce a constant electro-motive force; but in no instance of which I am aware has the excitement of the field been effected by a circuit derived from the main, and the electro magnet, through the instrumentality of which the resistance of the field is varied, been included in series with

the devices operated by the main circuit. This arrangement I have found to be productive of important and useful results.

In so far as the main features of the invention are concerned, the intermediate mechanism employed in conjunction with the rheostat and electro-magnet may be greatly modified or even dispensed with; but that described is both convenient and desirable, as it renders the device capable of a greater range of regulation and produces a more sensitive apparatus.

What I claim as my invention is—

1. The combination of a generator, a main circuit, devices included therein in series, a derived field-circuit, a variable resistance or rheostat included in the field-circuit, and an electro-magnet included in series with the devices in the main circuit for varying the resistance of the field-circuit, as and for the purpose set forth.

2. The combination of a generator, a main circuit, and a derived field-circuit, electrical devices included in series in the main circuit, a rheostat included in the field-circuit, an electro-magnet included in the main circuit, and mechanism for operating the rheostat in accordance with the varying attraction of the magnet, substantially as set forth.

3. The combination of a generator having main and field circuits, as described, a variable resistance or rheostat in the field-circuit, a pivoted lever provided with pawls and capable of a reciprocating movement, a shaft for operating the rheostat, ratchet-wheels with which the pawls may be caused to engage, and an electro-magnet for controlling the position of said lever, all substantially as set forth.

4. The combination, with a rheostat, of a shaft for shifting the contacts of the same, ratchet-wheels g d, reciprocating pawl-lever E, and electro-magnet G, swinging lever or frame B, shaft A, and a crank-connection from said shaft to the frame B, as and for the purpose set forth.

In testimony whereof I have hereunto set my hand this 21st day of February, 1883.

EDWARD WESTON.
